BREAKFRONT OR THE LIKE

Joseph E. Adkinson, 3807 Leland St.,
Chevy Chase, Md. 20015

Filed Apr. 17, 1970, Ser. No. 22,483

Term of patent 7 years

Int. Cl. D6—04

U.S. Cl. D33—13

FIG. 1 is a view in front elevation of the breakfront.
FIG. 2 is a view in side elevation of the breakfront of FIG. 1.

FIG. 3 is a top plan view of the breakfront of FIG. 1.
The side of the article not shown is a mirror image of the side shown while the back is plain and unornamented.

I claim:

The ornamental design for a breakfront or the like, substantially as shown and described.
